UNITED STATES PATENT OFFICE.

LLOYD BLACKMORE, OF HIGHLAND PARK, MICHIGAN, ASSIGNOR TO CAMPBELL WOOD,
OF DETROIT, MICHIGAN.

ADVERTISING RACK.

Application filed May 12, 1924. Serial No. 712,610.

It is the primary object of my invention to construct an adjustable rack in which advertising pamphlets or other literature or even articles of merchandise may be placed 5 in a manner to advantageously display them and prevent their being recklessly scattered about.

In a great many public places, including sales rooms, it is customary to place advertising pamphlets or other literature in boxes 10 or upon tables so that the public generally may take or examine copies thereof. In such cases it inevitably follows that the advertising matter is scattered about and so 15 left as to present a disheveled appearance to the containers or tables and, where more than one type of advertising is used, to mix the various types so as to render difficult the selection of one desired type by the user. It 20 is one of the objects of my invention to provide a device of simple and economical construction which will obviate the above difficulties by arranging the advertising matter in a neat and appealing manner and prevent 25 the same being scattered about recklessly.

With the above and other objects in view, my invention consists in the arrangement, combination and construction of the various 30 parts of my improved device as described in the specification, claimed in my claims and shown in the accompanying drawings in which:

Fig. 1 is an elevation of a modified form of my improved device.

Fig. 2 is a sectional view taken on line 35 5—5 of Fig. 4.

Fig. 3 is a sectional view taken on line 6—6 of Fig. 4.

Fig. 4 is a detailed view showing a modification of the end of a supporting arm.

I have provided a construction which may be built up or assembled complete before being attached to the display board, and have also made use of a single guide 45 member for all of the arms. In this construction I have shown a bottom plate 25 and a top plate 26 joined together at the corners thereof by providing an aperture in the top plate 26 and punching a portion of the plate 25 therethrough and then riveting the punched out portion over the edges of the opening in the plate 26 as at 27. A single guide member 28 having enlarged end 50 portions 29 is then secured thru the two plates 25 and 26 at approximately their

centers, the said guide member 28 also extending thru the slots 30, 31 and 32 of the arms 33, 34 and 35.

It will be noted that the arm 34 is positioned between the arms 33 and 35 so as to 60 space them and obviate the likelihood of either of these side arms moving when the other is moved.

The arms are held in the positions to which they are moved by the frictional contact between the plates 25 and 26. In order to increase the frictional contact, the metal of either of the said plates or both may be slightly deformed so as to cause it to rise around the central portion and to be depressed around the intermediate portion 70 against which the arm members will bear, thus imparting a certain spring action to the plate.

It will be noted in the foregoing construction that the device is assembled before attachment to the display board 5 and in order to so attach it, tacks 36 may be driven 75 thru the apertures in the corners of the plates into the board.

In the modified form of arm shown in Fig. 7 I have embodied a detachable end portion for the arm so as to assist in packing for shipping purposes, and also to permit the use of heavy material in the end portions when 80 heavy merchandise is desired to be displayed. In this construction I have disclosed a groove 85 37 in the flat portion 38 of the arm, said groove terminating in an aperture 39. The end portion 40 is provided with a pair of spaced lugs 41 adapted to bear on their inner 90 adjacent edges against the sides of the groove 37 and a tongue 42 having a projection 43 thereon, the tongue being adapted to rest in the groove 37 and the projection 43 being 95 adapted to extend thru the aperture 39.

Any number of these racks of any desired size may be placed upon a display board so as to accommodate varying pieces of literature, advertising matter or merchandise with 100 the result that each type will be neatly and attractively displayed.

It is obvious that various changes may be made in the arrangement, combination and construction of the various parts of my improved device without departing from the spirit of my invention, and it is my intention to cover by my claims such changes as may be reasonably included within the scope 105 thereof.

What I claim is:

1. A device of the class described, comprising a pair of plates, supporting arms positioned between the plates and adapted to slide therein, at least one of said plates being deformed so as to provide a yieldable portion bearing against at least one of said arms.
2. A device of the class described, comprising a pair of plates, supporting arms positioned between the plates and adapted to slide therein, at least one of said plates being deformed so as to provide a yieldable portion bearing against at least one of said arms.
- 10 3. A device of the class described comprising a pair of plates joined together at their corners, supporting arms extending between said plates thru the unjoined portions and adapted to slide between the plates, and means adapted to limit the sliding movement of the arms in both directions.
- 15 4. A device of the class described comprising a pair of plates joined together at their corners, supporting arms extending between said plates thru the unjoined portions and adapted to slide between the plates, and means adapted to limit the sliding movement of the arms in both directions, said arms
- 20 being adapted for positioning as desired by frictional binding of the plates.
5. A device of the class described comprising a pair of plates, one having bent corners attached to the other, supporting arms disposed between the plates thru the portions between the bent corners and means limiting movement of the arms in both directions between the plates.
- 25 6. A device of the class described, comprising a pair of plates, supporting arms positioned between the plates and adapted to slide therein, at least one of said plates being deformed so as to provide a yieldable portion bearing against at least one of said arms, a slot in each of said arms and a guide positioned in said plates and extending in said slots so as to limit the movement of said arms, said guide consisting of a headed pin extending thru the plates.
- 30 7. An advertising device having arms extended therefrom, a groove in said arm and an aperture adjacent said groove, an end portion having spaced lugs thereon adapted to embrace said arm on one side, one on either side of said groove, and another lug thereon adapted to fit into said groove on the opposite side of said arm, said lug having a tongue on the end thereof adapted to engage in said aperture.

LLOYD BLACKMORE.
